UNITED STATES PATENT OFFICE.

GEORGE W. BAKER, OF CHICAGO, ILLINOIS.

AUTOMATIC LUBRICATING APPARATUS.

SPECIFICATION forming part of Letters Patent No. 234,383, dated November 16, 1880.

Application filed June 15, 1880. (No model.)

To all whom it may concern:

Be it known that I, GEORGE W. BAKER, of Chicago, in the county of Cook and State of Illinois, have invented certain new and useful 5 Improvements in an Automatic Lubricating Apparatus; and I do hereby declare the following to be a full, clear, and exact description of the invention, that will enable others skilled in the art to which it appertains to construct and 10 make use of the same, reference being had to the accompanying drawings, and to letters and figures of reference marked thereon, forming a part of this specification.

This invention relates to that class of lubricators that are especially intended to lubricate the interior working parts of the valve-chambers and cylinders of steam-engines, and is adapted to be automatically operated, and to lubricate these parts by the action or influence 15 of the vacuum formed in the valve-chamber and cylinder when not working steam or by hydrostatic pressure produced in connection with this apparatus, and is so constructed and arranged as to secure a reliable and economical feed of oil.

Figure 1 is a side elevation of my improved lubricating apparatus, showing the form of construction and manner of attaching the device to the steam-pipe of a stationary engine. 20 Fig. 2 is a front elevation of the same, showing the condensing-chamber broken away and placed at the left; Fig. 3, a longitudinal central section in the plane $x x$, Fig. 1, the condensing-chamber being broken away and placed at the left. Fig. 3½ is a longitudinal 25 central section of a disconnected detail. Fig. 4 is a longitudinal central section in the plane $y y$, Fig. 3, showing the condensing-chamber broken away and placed at the right. Fig. 5 is a side elevation of part of a locomotive-boiler, showing the lubricating apparatus attached to the head thereof; and Fig. 6, an end view of the same. Fig. 7 shows the lubricating 30 apparatus attached to the head of a locomotive-boiler, the steam-pipe leading to the condensing-chamber and the oil-conducting pipe being both connected to the dry-pipe in the inside of the boiler; and Fig. 8, a view of the same, showing the oil-conducting pipe leading directly to the valve-chamber of the engine instead of into the dry-pipe.

Having thus shown by the several figures in the drawings the different ways of arranging and attaching the lubricating device, I will now proceed to describe the general construction 55 and operation of the same more in detail.

Referring to the drawings, A represents the oil reservoir or receptacle, which is ordinarily composed of glass, but may be composed of any material suitable for the purpose. This 60 reservoir is cylindrical in form, the two ends thereof being closed by means of the flanged metal disks a , which are securely clamped to the ends of the reservoir A by the bolts or rods a' , a packing-gasket of any suitable elastic material being interposed between the ends of the oil-reservoir and the clamped disks for the purpose of preventing leakage and forming substantially an air-tight receptacle. 65

A transparent oil-reservoir is preferred, as 70 the quantity of oil contained therein is readily observed, and by providing the same with graduated lines or proper indicating-characters the exact amount of oil being fed is known at all times, and the flow can be regulated accordingly. 75

As shown in Fig. 1 of the drawings, the apparatus is designed for use in connection with a stationary engine, and is attached to the steam-pipe of the same. The condensing-chamber B is placed at a much higher altitude than the oil-reservoir, so as to insure at 80 all times an excessive pressure in the oil-reservoir, and force a continuous flow of oil into the steam-pipe. The pipe C connects the condensing-chamber with the oil-reservoir, and the water from the condensing-chamber B passes down, and is discharged into the bottom of the oil-reservoir through the vertical pipe D, (shown in Fig. 3 of the drawings,) this 85 pipe D having connection with and forming a continuous passage from the condensing-chamber to the inside lower end of the oil-receptacle. 90

The vertical tube 9, located on the inside bottom of the oil-reservoir A, and extending upward therefrom to a short distance above the end of the pipe D, as shown in Fig. 3 of the drawings, is for the purpose of forming a trap at this point, thereby preventing the water 95 from being drawn below the level of this tube, and keeping the oil out of the passage or pipe 100

D, communicating with the condensing-chamber. This vertical tube incloses the lower open end of the pipe D, but it is of a larger area, therefore does not in the least obstruct the free passage from the condensing-chamber to the oil-reservoir.

When this device is employed in connection with a stationary engine steam is admitted to the condensing-chamber by opening the globe-valve 10, which has a proper connection with the steam-pipe, and the flow of the water from the condensing-chamber into the oil-reservoir is regulated by the globe-valve 11, and the passage of oil from the reservoir into the steam-pipe is regulated by means of the globe-valve 12. The ball-valve 13, placed in the oil-passage above the reservoir, closes the communication at this point, between the reservoir and the glass indicating-tube 14, as shown in Figs. 3 and 4 of the drawings. Arranged above the ball-valve 13, and operating in connection therewith, is the spiral spring 15, which prevents the ball-valve from entirely closing the passage when back-seating in the cage 16, in closing the same and allowing the oil to pass upward. The nozzle 17 and the cage 16, in which the ball-valve back-seats are formed, are shown in longitudinal central section in Fig. 3½ of the drawings. The tapering end of the nozzle 17 extends into the lower end of the glass indicating-tube 14, as shown in Fig. 3 of the drawings.

When it is desirable to put this lubricating apparatus into practical operation, the globe-valve 10 should be opened and the steam allowed to enter and condense in the condensing-chamber B. The valve 11 should next be opened and the water from the condensing-chamber allowed to enter and fill the oil-reservoir, and also pass up into and fill the glass indicating-tube 14. It is intended in this connection that this glass indicating-tube shall at all times be kept full of water, the oil passing up through the same. When the oil-reservoir is filled with water the communication between the reservoir and the condensing-chamber should be closed, and the waste-valve 18, located in the under side of the reservoir, should be opened and the water discharged, the ball-valve trapping the water in the glass tube. The screw-cap 19, closing the opening leading to the interior of the oil-reservoir, should now be removed and the reservoir filled with oil and the screw-cap replaced, tightly closing the opening. The valve closing the passage leading from the condenser should be slowly opened and the full pressure admitted from the condenser to the reservoir, and as the water is forced into the reservoir it expels the oil out and upward through the water in the glass indicator, the oil leaving the tapering end of the nozzle in the form of drops, the flow of oil passing into the steam-pipe and mingling with the steam, being regulated by the valve 12, the ball-valve device

preventing a back-pressure from entering and fracturing the oil-reservoir.

When using this lubricating device in connection with a stationary engine the hydrostatic pressure alone is depended upon and 70 supplies a continuous feed.

When it is designed to attach and make use of this lubricating apparatus on locomotive-engines, the same general construction is observed as that already described in connection with a stationary engine.

As shown in Figs. 5 and 6 of the drawings, which represent the device attached to the head of a locomotive-boiler, the pipe 20 connects the condensing-chamber attached to the lubricating apparatus with the dry-pipe leading to the engine, and the oil-conducting pipe 21 leads into andmingles the oil with the steam in the steam-dome attached to the boiler before the same passes to the engine. By 85 this arrangement the apparatus will only feed oil when the throttle-valve is open and the engine is working steam. When the throttle-valve of the engine is closed, that, of course, shuts the steam out of the condensing-chamber at the same time.

Fig. 7 shows the lubricating apparatus attached in the same manner as shown in Figs. 5 and 6, excepting that the oil-conducting pipe leads into the dry-pipe of the engine at a point 95 below where steam is taken to form the pressure in the condensing-chamber. This connection causes the lubricator to become a continuous feeder by the force of the hydrostatic pressure when the engine is working steam, and by 100 the suction of the vacuum when the engine is running dry.

Fig. 8 shows the oil-conducting pipe so arranged as to lead directly to the valve-chamber of the engine, which also gives a continuous feed. I prefer this connection for the oil-conducting pipe, as it enables me to keep the oil comparatively cool until it reaches the valve-chamber of the engine, whereas when the oil is fed into the dry-pipe, it is subjected 110 to the heat surrounding the same.

Having thus described my invention, what I claim, and desire to secure by Letters Patent, is—

1. In an automatic lubricating apparatus, 115 the combination, with a substantially air-tight oil-reservoir, of the vertical pipe D having a continuous connection with the condenser B, the tube 9, the ball-valve 13, the spiral spring 15, the cage 16 having the tapering nozzle 17 formed integral therewith, and the transparent indicating-tube 14, all arranged and operating as set forth.

2. An automatic lubricating apparatus, consisting, essentially, of a transparent oil-reservoir substantially air-tight, and having arranged in connection therewith a condensing-chamber adapted to take steam from the dry-pipe inside of the boiler, whereby the apparatus will stop feeding oil when the steam is 130

shut out of the dry-pipe, and the oil-conducting pipe leading into the steam-dome mingles the oil with steam on the interior thereof, thereby lubricating the steam only when the 5 throttle-valve of the engine is open and the same is working under a steam-pressure, substantially as herein shown and described.

3. A lubricating apparatus having a condensing-chamber attached thereto, which has 10 a proper connection with and takes steam from the dry-pipe, and the oil-conducting pipe leading directly to the valve-chamber of the engine, thereby adapting the apparatus to feed oil only by hydrostatic pressure when the 15 engine is working steam, when arranged substantially as herein shown and described.

4. In a lubricating apparatus substantially of the character hereinbefore described, the

combination of the following elements, consisting essentially of the transparent oil-reservoir A, the vertical pipe D arranged on the interior thereof, the vertical tube 9, the pipe C, the condensing-chamber B, the ball-valve 13, the spring 15, the tapering nozzle 17, the different arrangements and connections of the 20 pipes leading to the condensing-chamber and oil-conducting pipes, as herein shown and described, and the several globe-valves for adjusting and regulating the operations of the lubricating apparatus, all constructed and arranged as set forth, and for the purposes specified. 25

GEORGE W. BAKER.
